UNITED STATES PATENT OFFICE.

ALBERT WERNER, OF LIBERTY, NEW YORK.

PORTABLE DARK ROOM.

SPECIFICATION forming part of Letters Patent No. 694,221, dated February 25, 1902.

Application filed March 20, 1901. Serial No. 52,067. (No model.)

To all whom it may concern:

Be it known that I, ALBERT WERNER, a citizen of the United States, and a resident of Liberty, in the county of Sullivan and State of New York, have invented a new and Improved Portable Dark Room, of which the following is a full, clear, and exact description.

The invention relates to portable dark rooms such as shown and described in the Letters Patent of the United States, No. 666,988, granted to me on January 29, 1901.

The object of the present invention is to provide a new and improved portable dark room arranged to enable a photographer to readily fill plate-holders and develop exposed plates or films, to allow of conveniently regulating the amount of light admitted to the interior of the dark room, to enable the operator to temporarily withdraw from the main box without danger of light striking a plate in the process of developing, and to insure a constant supply of fresh air to the interior of the box.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement with the front swung into an open position. Fig. 2 is an enlarged transverse section of the improvement on the line 2 2 in Fig. 4. Fig. 3 is a longitudinal section of the same on the line 3 3 in Fig. 4 and with the front closed; and Fig. 4 is a sectional plan view of the same on the line 4 4 in Fig. 2 and with the front open.

The improved portable dark room is provided with a main box A, on the front end of which is hinged a cover B, adapted to be fastened by a suitable fastening device B' to the main box, as is plainly illustrated in Fig. 3. The cover B is provided with a pane B² of translucent material, preferably orange or red glass, and the said pane is adapted to be covered on the inside by a shield B³ of transparent ruby fiber-cloth or the like attached to a frame hinged to a frame B⁴, secured to

the cover B and likewise covered with transparent ruby fiber-cloth, so that when the shield B³ is swung into a lowermost position, 55 as shown in Fig. 3, the pane B² and the said cover prevent strong rays of light from entering into the interior of the box. When the device is used, however, for developing purposes, the cover B is swung up, so as to 60 allow rays of light to pass into the box by way of the pane B², to enable the operator to see sufficiently for performing the desired operations.

The sides of the main box A are provided 65 with openings A', extending rearwardly from the front end of the sides, and said openings are adapted to receive flanges C² of auxiliary boxes C C', extending at right angles outwardly from the sides of the main box A, as 70 is plainly shown in Figs. 1, 2, and 4, the boxes being locked in place in the openings A' by the cover B when the latter is in a closed position. When the boxes C C' are in position on the sides of the main box A, they open to 75 the interior of the main box to enable the operator to place trays in said auxiliary boxes when using the dark room, as hereinafter more fully described. The auxiliary box C' is formed with an auxiliary partition C³ to produce a top and bottom compartment, of which the upper compartment is normally closed by a suitable hinged door C⁴, as is plainly shown in Fig. 2. By this arrangement the upper compartment can be used for placing filled 80 trays with partly-developed plates therein and keeping the plates from being light-struck in case the operator withdraws his head and arms from the dark room.

In the top of the main box A, near the front 90 end thereof, is arranged an opening A², opening into a hood D, of flexible material, and secured to the top of the main box A, around the said opening, as is plainly indicated in the drawings. The outer end of this hood D 95 is provided with an elastic band D', adapted to pass around said end at the time the end is around the operator's neck, so as to securely close the end of the hood D, and thereby prevent rays of light from passing to the interior 100 of the main box when the operator uses the dark room. A cover E, of flexible material, surrounds the hood D and is, with the latter, secured to the top of the box, and this flexi-

ble cover prevents any possibility of rays of light penetrating the meshes of the hood, and consequently prevents any rays from entering the interior of the main box.

- 5 In the sides of the main box A at the rear of the auxiliary boxes C C' are formed openings leading to sleeves F F', of flexible material, and adapted to be engaged by the arms of the operator, the outer ends of said sleeves 70 being formed with elastic draw-bands F² to hold the ends of the sleeves in firm position on the operator's arm to prevent rays of light from passing through the sleeves to the interior of the box A.
- 15 In the rear portion of the main box A and near the top thereof are arranged guideways A⁴ for a box-shelf G, preferably formed with two compartments normally closed at their front ends by suitable doors G', as indicated 75 in Figs. 2 and 3. Into the hood adjacent to the opening A² extends a mouthpiece H for the operator to breath in, said mouthpiece opening into a channel H', extending rearwardly to the back of the main box and then 80 sidewise to an opening H² in the side of the main box, as indicated in Fig. 4. On the under side of the top of the main box and at the sides thereof are arranged channels I I', opening at their front ends into the interior of the 85 box and connecting at their rear ends with side openings I², formed in the sides of the main box and leading to the outside. Now by constructing the channels H' and I I' with angles, as shown, it is evident that rays of light cannot pass through these channels from the outside to the interior of the box; but at the same time the channel H' forms a discharge for the breath of the operator, while the channels I I' allow fresh air to pass into 90 the interior of the main box to supply sufficient air to the operator to enable the operator to work comfortably while filling plate-holders or developing plates, &c.

In order to enable the operator to securely 45 fill plate-holders with plates, the operator first places the plates in the box and with them the holders to be filled and then closes the door or cover B and swings the shield B³ into a closed position, as indicated in Fig. 3, to 50 render the interior of the main box as dark as possible. The operator now places his head into the hood D and his arms into the sleeves F F' to work within the box with his hands and to see the operations by looking 55 through the opening A³ into the interior of the box. The operator then fills the plate-holders in the usual way.

In developing plates five trays are usually employed—two for the hypo, one for the water, 60 and one for the developer, and one large tray for preventing water from spilling inside of the box. The first operation is to place the plates exposed and contained in the holders in the auxiliary compartment C, and when 65 the operator is ready to proceed the holders are successively removed and opened and the exposed plates withdrawn and placed in the

box-shelf G. The doors G' are closed, so that rays of light are not liable to strike the exposed plates. The holders are then removed 70 entirely from the dark room, allowing of plenty of room to operate, and thus preventing the holders from getting wet or endangering them in any way. The operator now proceeds in the usual manner to develop the exposed plates successively or in pairs in the trays held in the front part of the main box A. The operator may at any time during the operation withdraw from the box without danger of injury to any of the plates, whether 80 undeveloped or in the process of developing. Such plates can be kept securely locked in the box-shelf and a partly-developed plate can be placed in the compartment in the auxiliary box C', provided with a door C⁴. 85

When it is desired to transport the dark room from one place to another, the auxiliary boxes C C' are detached from the sides of the main box and placed inside thereof through the door B, then in an open position, and then 90 the hood H and its cover E are pushed through the opening A² to the inside of the box, and the sleeves F F' are treated in a like manner, so that the whole dark room can be readily moved from one place to another or carried 95 conveniently and comfortably.

The provision of the auxiliary boxes C C' allows of continuous development. This is a very important feature of the dark room, as one plate after another may be developed 100 without delay and in much quicker time than heretofore done.

Having thus fully described my invention, I claim as new and desire to secure by Letters Patent—

1. A portable dark room, comprising a main box having an inner flexible hood secured around an opening in the top of the box, and a flexible protective cover separate from and loosely surrounding the hood and likewise fastened to the top of the box, as set forth. 105

2. A portable dark room, comprising a main box having a flexible hood secured around an opening in the top of the box, and having an elastic draw-band at its outer end, and a flexible protective cover separate from and loosely surrounding the hood and likewise fastened to the top of the box, as set forth. 115

3. A portable dark room, comprising a main box having its front end closed by a cover having a pane and adapted to be opened, the sides of the box having openings extending rearwardly from the opening in the front end, and auxiliary boxes open only at one side and adapted to be inserted in said openings when 120 said cover is open, the cover when closed locking said auxiliary boxes in place, as set forth.

4. A portable dark room, comprising a main box having its hinged cover end closed by a front having a pane, the sides of the box having openings extending rearwardly from the opening in the cover end, guideways along the upper and lower ends of said side open- 125

ings, and auxiliary boxes open at one side and adapted to be inserted in said guideways when the cover is open, the cover when closed locking said auxiliary boxes in place, as set forth.

5. A portable dark room, comprising a main box having its hinged cover end closed by a front having a pane and provided on its inner face with a shield for the pane, the sides of the box having openings extending rearwardly from the opening in the front end, and auxiliary boxes open only at one side and adapted to be inserted in said openings when said cover is open, the cover when closed locking said auxiliary boxes in place, said auxiliary boxes having horizontal partitions to form upper and lower compartments.

10. A portable dark room, comprising a main box having its hinged cover end closed by a front having a pane and provided on its inner face with a shield for the pane, the sides of the box having openings extending rear-

wardly from said front end, and auxiliary boxes open only at one side and adapted to be inserted in said openings when said cover is open, the cover when closed locking said auxiliary boxes in place, said auxiliary boxes having horizontal partitions to form upper and lower compartments, one of said compartments being normally closed at the inner side by a hinged door, as set forth.

15. In a portable dark room, the combination with the main box having at its front a hinged cover provided with a pane, of a shield for the pane on the inner face of the cover, said shield comprising a fixed section and a hinged section, as set forth.

20. In testimony whereof I have signed my name to this specification in the presence of two subscribing witnesses.

ALBERT WERNER.
